CLAIM

The ornamental design for a medical examination table, as shown and described.

DESCRIPTION

FIG. 1 is an isometric view of a medical examination table of the present invention shown in a first position.

FIG. 2 is a second perspective view thereof;

FIG. 3 is a left side elevation view of the medical examination table of FIG. 1, with the right side view being a mirror image thereof.

FIG. 4 is a front side elevation view of the medical examination table of FIG. 1.

FIG. 5 is an isometric view of the medical examination table of FIG. 1 shown in an alternate position.

FIG. 6 is an isometric view of a medical examination table of the present invention shown in another alternative position.

FIG. 7 is a top plan view of the medical examination table of FIG. 6.

FIG. 8 is a left side elevation view of the medical examination table of FIG. 6, with the right side view being a mirror image thereof; and,

FIG. 9 is a first perspective view of a probe for an ultrasonic diagnosis apparatus showing my new design according to a second embodiment.

The dash lines in the drawings depict environmental subject matter and form no part of the claimed design. The dot dash dot broken lines depict the boundaries of the claim and form no part thereof.

1 Claim, 9 Drawing Sheets
